US00D533253S

(12) **United States Design Patent** (10) **Patent No.:** **US D533,253 S**
Luettgen et al. (45) **Date of Patent:** **** Dec. 5, 2006**

(54) **ELLIPTICAL SHOWER HEAD**

(75) Inventors: **Harold A. Luettgen**, Windsor, CO (US); **Michael J. Quinn**, Windsor, CO (US)

(73) Assignee: **Water Pik, Inc.**, Fort Collins, CO (US)

(**) Term: **14 Years**

(21) Appl. No.: **29/216,507**

(22) Filed: **Nov. 3, 2004**

(51) **LOC (8) CL. 23-01**

(52) **U.S. CL. D23/229; D23/213**

(58) **Field of Classification Search D23/213, D23/229, 230; 239/282, 283**

See application file for complete search history.

(74) *Attorney, Agent, or Firm*—Dorsey & Whitney LLP

(57) **CLAIM**

The ornamental design for an elliptical shower head, as shown and described.

DESCRIPTION

FIG. 1 is a perspective view of a first embodiment of an elliptical shower head showing our new design;

FIG. 2 is a front view of the elliptical shower head of FIG. 1;

FIG. 3 is a rear view of the elliptical shower head of FIG. 1;

FIG. 4 is a left side view of the elliptical shower head of FIG. 1;

FIG. 5 is a right side view of the elliptical shower head of FIG. 1;

FIG. 6 is a top view of the elliptical shower head of FIG. 1;

FIG. 7 is a bottom view of the elliptical shower head of FIG. 1;

FIG. 8 is a perspective view of a second embodiment of an elliptical shower head showing our new design;

FIG. 9 is a front view of the elliptical shower head of FIG. 8;

FIG. 10 is a rear view of the elliptical shower head of FIG. 8;

FIG. 11 is a left side view of the elliptical shower head of FIG. 8;

FIG. 12 is a right side view of the elliptical shower head of FIG. 8;

FIG. 13 is a top view of the elliptical shower head of FIG. 8;

FIG. 14 is a bottom view of the elliptical shower head of FIG. 8;

FIG. 15 is a perspective view of a third embodiment of an elliptical shower head showing our new design;

FIG. 16 is a front view of the elliptical shower head of FIG. 15;

FIG. 17 is a rear view of the elliptical shower head of FIG. 15;

FIG. 18 is a left side view of the elliptical shower head of FIG. 15;

FIG. 19 is a right side view of the elliptical shower head of FIG. 15;

FIG. 20 is a top view of the elliptical shower head of FIG. 15; and,

FIG. 21 is a bottom view of the elliptical shower head of FIG. 15.

The broken line showing is for illustrative purposes only and forms no part of the claimed design.

1 Claim, 12 Drawing Sheets
